UNITED STATES PATENT OFFICE

HENRY S. BEERS, OF WESTPORT, CONNECTICUT, ASSIGNOR TO THE TURBO-MIXER CORPORATION, OF NEW YORK, N. Y., A CORPORATION OF NEW YORK

MIXING APPARATUS

Application filed January 10, 1930. Serial No. 419,799.

My invention relates to mixing apparatus of the turbo-impeller type, and especially to an improved construction or arrangement in which the annular flow directing plates 5 are formed or arranged as parts of the stationary deflector, and co-operate with the rotor or impeller blades to provide the desired annular flow controlling channel or nozzle for the mix.

Heretofore it has been customary to provide the annular flow controlling plates as parts of the impeller. The invention provides for simplifying and reducing the cost of impeller construction and reduces the weight of the impeller by incorporating the flow controlling plates in the deflector structure, which is stationary and in which added weight is not objectionable.

The characteristics and advantages of the invention are further sufficiently explained in connection with the following detail description of the accompanying drawings, which show representative embodiments. After considering these examples, skilled persons will understand that many variations may be made within the scope of the appended claims.

In the drawings:

Fig. 1 is a top plan of essential parts of a turbo-mechanism of duplex type, embodying the invention in one form.

Fig. 2 is a section in an axial plane.

Fig. 3 is a fragmentary top plan of a mechanism of simplex type.

Fig. 4 is an axial section of the same.

Fig. 5 is a top plan on reduced scale showing a modified impeller blade form or arrangement.

Fig. 6 is a fragmentary section in an axial plane showing the blade arrangement of Fig. 5 as embodied in an impeller of simplex type.

In Figs. 1 and 2 I show a mixer of what is known as duplex type, providing for intake of the mix in both directions, that is, from both sides, to the impeller and substantially radial discharge with proper flow control.

The impeller comprises a central or hub portion 1 which may be chambered as at 2,

for lightness, and which is extended to form a circular flange or plate 3 carrying the vertical impelling blades 4, which may be cast integral with or secured to the hub and plate structure. In this example the inward slanting edges 5 of the impeller blades are located substantially outward from the hub; otherwise the blades may extend all the way to the hub and be connected to or formed integral therewith, as sufficiently explained below in connection with a modification of the simplex type of impeller, Figs. 5 and 6.

In any case the impeller blades have curvature and arrangement for proper propulsion of the mix flowing toward the impeller in opposite axial directions, and discharge of the mix in tangential directions.

Co-operating with the impeller is a stationary deflector structure comprising upper and lower blade supporting and flow directing annular plates 6, which are of generally dished form, providing entrance or throat portions 7 and somewhat converging outer portions 8 which conform to the upper and lower edge contours of the impeller blades 4, with slight clearance. These stationary flow directing plates 6 are designed to provide a substantially annular nozzle co-operating with the impeller blades and of such form that the impelled mixture will flow with maximum velocity to the point of discharge in substantially tangential directions at the outer edges of the impeller blades.

Co-operating with the flow directing plates are vertical deflecting blades 10, curved and arranged as sufficiently shown in Fig. 1 to receive the tangentially moving mixture and direct it to flow outward in radial directions.

These deflector blades may be formed integrally with the flow directing plates 6, or separate and connected to them. When desired, other flow directing plates 12 may be provided intermediate blades 10, these plates 12 being substantially perpendicular to the vertical blades, curved, and arranged at alternately upward and downward angles,

as clearly indicated in solid and dotted lines in Fig. 2, to direct desired portions of the

mixture to flow upward and downward and in radial planes.

The impeller is supported and driven by a shaft 15, and in the duplex type where the deflector is located at an intermediate position in the mixing tank and away from the tank bottom or top, the deflector may be supported in proper relation to the impeller in any convenient way, as by struts 16 extending to the tank side wall.

Figs. 3 and 4 shows the same structural principle embodied in a mixer of simplex type, that is, one in which the impeller 20 is located close to the tank bottom 21 and material flows into the impeller in only one direction, namely, axially downward. In this simplex type the impeller blades 22 may be connected by intermediate web or plate portions 23 which are of approximate stream line section and located at such an angle that they do not interfere with flow of material. The blades and plates or web members 23 may be connected by spaced arms or spokes 24 to a hub 25 mounted on the driving shaft 26. As a variation, the blades such as 22 of Figs. 3 and 4, may extend all the way to the hub; thus the blades 22. Figs. 5 and 6 may be complete involute blades and the arms or spokes 24 are of course in such case dispensed with; also in the duplex type, Figs. 1 and 2, the blades may be of complete involute form, extending to a central hub and dispensing with the supporting plate or septum structure 3 of Fig. 2.

For the simplex type of Figs. 3 and 4 the deflector 28 includes a single annular flow directing plate 29 generally similar to the plates 6 of the other example, this plate 29 being suitably dished to provide an entrance throat 30 and a flow space or channel of desired area.

The vertical deflecting blades 31 may be connected to or cast integrally with plate 29, and the entire deflector structure is secured to the tank bottom, as by screws or bolts.

I claim:

1. Mixing apparatus comprising a rotary bladed impeller including vertical blades of duplex type; and a stationary deflector forming in co-operation with the impeller blades an annular flow nozzle, said deflector comprising vertical deflector blades intermediate and supported by said plates, and additional flow directing blades substantially perpendicular to the deflecting blades and supported by said deflecting blades, said additional blades being inclined alternately at upward and downward angles to cause the discharged material to flow in corresponding directions in radial planes.

2. A rotary impeller comprising substantially vertical involute blades the upper and lower edges of which are free and diverge

from one another from the tips of the blades toward the inner ends of the blades; in combination with a stationary deflector comprising two annular nozzle forming plates one positioned adjacent the upper edges of the impeller blades and the other positioned adjacent the lower edges of the impeller blades, said deflector plates being inclined in conformity with the edges of the impeller blades and projecting beyond the tips of the impeller blades, and vertical deflecting blades extending between said plates.

3. A rotary impeller comprising substantially vertical involute blades the upper and lower edges of which are free and diverge from one another from the tips of the blades toward the inner ends of the blades, and annular partition means extending from blade to blade between the upper and lower edges of said blades; in combination with a stationary deflector comprising two annular nozzle forming plates one positioned adjacent the upper edges of the impeller blades and the other positioned adjacent the lower edges of the impeller blades, said deflector plates being inclined in conformity with the edges of the impeller blades and projecting beyond the tips of the impeller blades, and vertical deflecting blades extending between said plates.

4. Mixing apparatus comprising: a rotary impeller having vertical blades of duplex type; in combination with a stationary deflector comprising two stationary annular nozzle forming plates overlapping the impeller blades, one plate being positioned adjacent the upper edges of the impeller blades and the other being positioned adjacent the lower edges of the impeller blades, said plates also extending beyond the tips of the impeller blades, vertical stationary flow directing blades intermediate and supported by said plates, and additional flow directing blades substantially perpendicular to said stationary vertical blades and supported by said stationary vertical blades.

In testimony whereof I affix my signature.
HENRY S. BEERS.
